UNITED STATES PATENT OFFICE.

EDWARD CHARLES HOCK, OF BUFFALO, NEW YORK.

SMOKE-PREVENTING BOILER FURNACE.

Application filed May 31, 1921. Serial No. 473,670.

To all whom it may concern:

Be it known that I, EDWARD CHARLES HOCK, a citizen of the United States of America, residing at Buffalo, in the county 5 of Erie and State of New York, have invented certain new and useful Improvements in Smoke-Preventing Boiler Furnaces, whereof the following is a specification.

10 This invention relates to steam boiler furnaces which combine the properties of smokeless combustion, extensive direct heating surface and facility of regulating the smokeless combustion current with relation 15 to said extension heating surface.

This invention embodies certain improvements in the smoke preventing boiler furnaces heretofore patented to me by Patent No. 1,260,196 dated March 19, 1918.

20 The objects of this invention are to simplify the construction of my patented furnace aforesaid, to utilize to better advantage the heating effects of the waste products of combustion passing out thru the 25 back chamber of said furnace in heating air or other fluid fuel supplied to the combustion chamber and to adapt the furnace to a force feed of the air supplied to the primary combustion chamber over the surface of the 30 burning fuel therein and to the use of gas, oil or vapor thereof, water or vapor thereof commingled with the air current so supplied to said fire box.

In the accompanying drawings which 35 represent the preferred embodiment of the invention, Figure 1 represents a longitudinal vertical section of the boiler furnace taken on line 1—1 of Fig. 2.

Fig. 2 represents a horizontal section on 40 line 2—2 of Fig. 1.

Fig. 3 represents a transverse section on line 3—3 of Fig. 1.

Fig. 4 represents a transverse section on line 4—4 of Fig. 1.

45 Fig. 5 represents on an enlarged scale a vertical section on line 5—5 of Fig. 4 of the fluid fuel converter.

Fig. 6 represents on an enlarged scale a horizontal section of the furnace wall adjacent to the fire box showing the fluid fuel distributing pipe.

50 Fig. 7 represents on an enlarged scale a transverse section of said wall where the distributing pipe goes thru it.

The same reference numbers indicate corresponding parts in the different figures. 55

The furnace structure includes the general features of a well known type of boiler furnace, being divided into a boiler chamber 10 in which the boiler 20 is set, a primary combustion chamber 30 beneath the front portion of the boiler chamber, an ash chamber 40 below the primary combustion chamber, a secondary combustion chamber 50 beneath the rear portion of the boiler 60 chamber, a back chamber 60 at the rear of the boiler 20, a front chamber 70 at the front thereof, and a smoke stack 80 leading up from the chamber 70 and provided with a damper 81. 70

A central bridge wall 90 disposed below the boiler about midway of the length thereof, separate the secondary combustion chamber 50 from the primary fire chamber 30 and ash chamber 40. This bridge wall has 75 a concave arc-shaped bridge wall 91, which is preferably concentric with the boiler at some distance therefrom, and extends upward adjacent to the opposite sides thereof. The bridge thus forms an arc-shaped passage 41 between its top and the lower portion of the boiler, which passage establishes communication between the primary combustion chamber 30 and the secondary combustion chamber 50. 80

85 A rear bridge wall 100 disposed below the rear end of the boiler separates the back chamber or flue 60 from the secondary combustion chamber 40. This rear bridge wall has an arc-shaped top 101, which is preferably concentric with the boiler at some distance therefrom and extends upward on opposite sides thereof adjacent thereto. This bridge wall forms an arc-shaped passage 61 between its top and the lower portion of the boiler and this passage establishes communication between the secondary combustion chamber 50 and the back chamber 60. 90

95 The boiler 20 is of the fire tube type and its fire tubes 21 establish communication between the back chamber 60 and the front chamber 70 from which the stack 80 leads upward. The diameter of the boiler is less than the width of the boiler chamber 10 so 100 that spaces 11 and 12 are left between the furnace walls and the boiler on opposite sides of the latter. These spaces constitute 105

upward extensions of the combustion chambers 30 and 50 and terminate at the top of the boiler chamber, the top of the boiler being at the top of the chamber. These upper extension combustion chambers in connection with the lower combustion chambers provide a direct heating surface throughout the exterior of the boiler and operate to superheat the steam. The usual water supply pipe 22 passes thru the rear furnace wall, thru the rear bridge wall 100 and enters the boiler at any suitable point.

A deflector 65 is pivoted to the rear bridge wall 70 at the lower edge of the arc-shaped passage 61 and is adapted to close the lower part of said passage. This deflector is adapted to be swung backward to open said passage more or less for regulating the current of gases passing from the combustion chambers upward around the steam space of the boiler as hereinafter explained. This deflector is supported in a transverse rod 66 which extends from side to side of the back chamber 60. The rod 66 is provided with a hand wheel 67.

The parts above described are substantially the same as the corresponding parts in my patent aforesaid.

A fluid fuel converter 110 is mounted in the back chamber 60 where it is exposed to the heat of the hot gaseous products of combustion passing therethru from the secondary combustion chamber 50 to the smoke stack 80. This converter serves as a heater for air and gas, as a vaporizer for oil or water and as a mixer for these several fluids. This combined heater, vaporizer and mixer comprises in its preferred form, a horizontal receiving chamber 111, a horizontal delivery chamber 112 and a central horizontal mixing chamber 113. The receiving chamber 111 is connected with the mixing chamber by vertical pipes 114 and the mixing chamber is connected with the delivery chamber by vertical pipes 115. The outer surfaces of these several chambers and pipes are exposed to the heat of the escaping gaseous products of combustion passing thru the back chamber 60, and consequently heat the air and vaporize the oil or water passing therethru.

An air intake pipe 140 disposed at or near the top of the furnace extends thru the furnace wall from the exterior thereof into the back chamber 60 and is connected at its inner end with the receiving chamber 111 of the converter 110. The outer end of this intake pipe is preferably connected with a force feed apparatus, preferably in the form of a blower 145 operated by an electric motor.

The fluid fuel converter 110 is connected at its lower end by a three-way coupling 116 with laterally diverging pipes 121 and 122 at a point about on a level with or

slightly above the normal fire surface of the primary combustion chamber. These pipes connect at their outer ends with pipes 123 and 124 which pass thru the rear bridge wall 100 and extend longitudinally along the side walls of the secondary combustion chamber 50, thence are inclined outward thru the central bridge wall 90 and thence connect with longitudinal distributing pipes 130 and 131 disposed within the walls of the primary fire box or combustion chamber preferably on a level or thereabouts with the normal fire surface of said box. These distributing pipes are preferably provided with inturned extensions 132 and 133 which extend within the furnace wall opposite the front portion of the fire box at opposite sides of the door thereof. These distributing pipes and their lateral extensions are provided with discharge orifices 135 preferably in the form of tapering nozzles which project into openings 134 in the walls between the distributing pipes and the interior of the fire box. The inclined portions of the fluid fuel distributing pipes 130 and 131 are provided with inward extensions 136 and 137 located in the central bridge wall 90 and having nozzles 138 which discharge thru holes or lutes 139 in the walls of the secondary combustion chamber 50. These nozzles preferably discharge at an angle of forty five degrees more or less in an upward direction towards the bottom of the boiler which is exposed within said chamber.

The air intake pipe 140 delivers outside air to the receiving chamber 111 of the converter, whence it passes downward thru the pipes 114 into the mixing chamber 113, thence downward thru the pipes 115 into the delivery chamber 112. The air in passing thru the converter becomes highly heated and passes out therefrom thru the coupling 116, diverging pipes 121 and 122 and longitudinal pipes 123 and 124 to the distributing pipes 130 and 131, and thence into the furnace thru the nozzles 135. The air so supplied to the incandescent surface of the fire in the fire box is thoroughly heated to a high degree before being discharged into said box.

Means are provided for supplying a gaseous fuel in the form of gas other than air to the mixing chamber of the heater 110. The means shown for this purpose comprise a pipe 150 extending thru the wall of the back chamber 60 adjacent to the air intake pipe 140. This pipe is provided at its outer end with an enlargement 142 and an injector nozzle 152 connected with the air intake pipe 140 terminates within said chamber. A gas supply pipe 153 having a cock 154 is connected with a source of gas supply. The injector pipe or nozzle 152 induces a suction and forces a feed of fuel 130

gas mixed with more or less air thru the gas pipe 150, the inner end of which is provided with a distributing pipe 155 within the mixing chamber 113 of the converter 110. This pipe is provided on its opposite sides below its center with orifices 156 which spray the gas into said chamber.

Means are provided for supplying oil to the mixing chamber of the heater whereby 10 it may be vaporized and commingled with the air passing therethru to the fire box. The means shown for this purpose comprise an oil tube 160 leading to a source of oil supply and being provided with a stop cock 151. This oil tube connects with and supplies oil to the tube 150 thru which it passes to the mixing chamber.

Means are provided for supplying water to be utilized in the form of vapor or steam 20 in connection with the other fuel gases hereinbefore referred to. The means shown for this purpose comprise a water receiving chamber 170 having an inlet pipe 171 which extends thru the top thereof and discharges into said chamber near the bottom thereof. This pipe connects with a source of water supply and is provided outside the furnace wall with a stop cock 172. The receiving chamber is connected near its upper end by 25 a pipe 173 with the pipe 150. This chamber 170 is located within the back chamber 60 where it is exposed to the heat of the escaping gaseous products. The water admitted to the water chamber 170 is heated 30 thru the exposure of said chamber to said hot gases and passes out into the pipe 150. By the time it reaches the mixing chamber the water is partially vaporized on its way to the mixing chamber and after entry 35 into the mixing chamber and after entry 40 thereinto is fully converted into steam or superheated steam and mixes with the air which comes in thru the pipe 140.

By the means above referred to air alone may be distributed over the burning coals in 45 the fire box in a very hot state approximating the temperature of the incandescent coal. Natural or other gas may be commingled with said hot air; or oil in the form of vapor may be commingled with the air alone, 50 or with air and gas; and steam may be combined with the air and gas or air and oil or oil and gases or oil alone or gas alone as may be found most desirable or beneficial in the particular locality where the furnace is used.

55 The air intake 140 is provided with a Y-connection 141 with which the injector nozzle 152 is connected. One arm of the Y is provided with a damper 143 which may be opened and closed by any suitable means as 60 by cord or chain 144 which may be self regulating or otherwise. This chamber is opened for the admission of air by automatic flow when the force feed apparatus 145 is not in use. Thus there is a constant flow of air 65 provided for the converter whether or not the

force feed is used. The water vapor developed when water is supplied is converted into super-heated or dry steam while passing thru the converter and is thus in a condition to increase combustion within the fire box.

In the use of this furnace air admitted or forced in thru the air intake 140 passes into the receiving chamber of the converter 110, thence to the mixing chamber 113 thereof and thence to the delivery chamber thereof from 70 which it passes by the pipes 121, 122, 123 and 124 to the distributing pipes 130 and 131, and by them is discharged into the fire box over the incandescent coals thru the nozzles 135, and into the secondary combustion chamber 50 thru the branch pipes 136 and 137 and their nozzles 138 and 139. Thus a supply of heated air to facilitate and produce smokeless combustion is distributed over the coals of the fire box. If the vapor of oil is to be 80 added, the oil is supplied thru the pipe 150 to the mixing chamber of the converter and there mixed with the hot air which is supplied to the combustion chamber thru the distributing pipes aforesaid. If steam or the 85 vapor thereof is to be added, water is supplied thru the pipe 171 and chamber 170 to the pipe 150 and is thence discharged into the mixing chamber of the converter thru the jets 156 of the pipe 155.

The combustion current from the fire box passes along the bottom of the boiler in direct contact therewith thru the passage 41 into the secondary combustion chamber, thru said chamber along the bottom of the boiler and 90 thru the passage 61, past the deflector 65 into the back chamber 60, and in part upward around the boiler at each side thereof in direct contact with the boiler and thence 95 rearward thru the boiler chamber 10 into the back chamber 60; thence forward thru the fire tubes of the boiler into the front chamber 70 and thence upward thru the stack 80.

By manipulation of the damper 65, more or less of the combustion current is made to pass underneath the boiler thru the passages 100 41 and 61 and a greater or less proportion upward thru the extension combustion chambers 11 and 12. The combustion current 105 can thus be divided, regulated and varied to suit the conditions of combustion incident to the volume and condition of the air or fluid fuel admitted to the combustion chamber.

When it is desired to reduce the steaming power of the boiler, the deflector 65 is opened and when the boiler is to be run to its full capacity of steaming power, the deflector 65 is closed. When the deflector 65 115 is open and the stack damper is closed or partially closed the fire is checked and yet sufficient air is admitted to the combustion chamber to prevent the formation of smoke and when said deflector is closed an ample 120 125 130

quantity of air is likewise supplied to the combustion chamber to prevent the generation of smoke, and the current from the combustion chamber is thrown upward around the boiler on both sides thereof into direct contact therewith and with the steam space thereof whereby the greatest water heating effect is obtained together with superheating of the steam. When the deflector 65 is opened the stack damper 81 may be closed and when the deflector 65 is closed the stack damper 81 is partly open.

In the use of this furnace a large direct contact surface is obtained which is subjected to the heat of the intensified smokeless combustion induced in the combustion chambers and extension combustion chambers as hereinbefore stated. By the adjustment of the deflector 65 and further by the relative adjustment of the deflector 65 and damper 81, in connection with the vertical flues in the side walls of the combustion chamber which deliver the heated air and fluid fuel over the bed of fuel and in connection with the extension combustion chambers extending upward around the boiler to the top thereof, a thoro combustion may be obtained without waste of heat thru the stack, and the size of the stack may be reduced.

I claim as my invention:

1. A boiler furnace comprising a horizontal cylindrical boiler, back and front flue chambers at opposite ends thereof, flues connecting said chambers, a combustion chamber below said boiler, extension combustion chambers continuous with said combustion chamber and extending upward around said boiler on opposite sides to the top thereof and opening into said back flue chamber, a bridge wall between said combustion chamber and said back flue chamber and forming a passage between the lower part of the boiler and said wall, said passage connecting said combustion chamber with said back flue chamber, a deflector disposed in said passage, a converter consisting of a combination heater, vaporizer and mixer disposed in said back flue chamber, means for supplying air and oil to said converter, dis-

tributing pipes disposed on opposite sides of the fire box and provided with nozzles adapted to inject air and vaporous fuel into said fire box over the coals therein, and pipes connecting said converter with said distributing pipes.

2. The combination with a boiler furnace having primary and secondary combustion chambers and a back flue chamber in rear thereof, a converter mounted in said back flue chamber and consisting of a combination heater, vaporizer and mixer for fluid fuels, means for supplying said fuels to said converter, distributing pipes embedded in the walls of said primary combustion chamber and provided with nozzles projecting into openings in said walls for discharging the fluid fuel into said primary combustion chamber, and diverging and side pipes connecting said converter with said distributor.

3. A converter for fluid fuel to be supplied to a steam boiler furnace consisting of a top receiving chamber, a bottom delivery chamber, an intermediate mixing chamber, pipes connecting said bottom and top chambers with said mixing chamber, an air intake pipe connected with said top chamber, delivery means connected with said bottom chamber, a jet pipe projecting into said mixing chamber, and means for supplying water to said jet pipe.

4. The combination with a steam boiler furnace, of jet distributing pipes disposed in the walls of the fire box above the grate, a converter disposed in the back flue chamber thereof, pipes connecting said distributing pipes with the delivery chamber of said converter, an air intake pipe connected with the receiving chamber of said converter, a jet pipe extending into the mixing chamber of said converter, a fluid fuel pipe connected with said jet pipe at its feed end, an injector mounted on said air intake pipe and engaging said fuel feed pipe, and an air forcing apparatus connected with said air pipe and operative to simultaneously force air thru said air intake and fluid fuel thru said fuel feed pipe to different parts of said converter and thence to said distributing pipes.

EDWARD CHARLES HOCK.
